UNITED STATES PATENT OFFICE.

ARTHUR W. SIEVERS, OF VALPARAISO, INDIANA, ASSIGNOR TO NOAH S. AMSTUTZ.

SCINTILLATING SIGN.

Application filed January 24, 1924. Serial No. 688,315.

My invention relates to scintillating signs, and it more especially consists of the features hereinafter pointed out in the annexed claims.

5 The purpose of my invention is to produce a simplified advertising sign that will spell words, sentences, etc., letter by letter; that will display entire words, sentences, etc., in repetitive order; that will combine transparent with translucent effects; that is entirely automatic in its operation; that is susceptible of indefinite enlargement or expansion; that is portable; that makes a minimum demand for electric current; and that on account of its 10 extraordinary simplicity avoids the use of a driving motor, connecting gears, levers, etc.

With these and other ends in view, I illustrate in the accompanying drawing such instances of adaptation as will disclose the 15 broad underlying features without limiting myself to the specific details shown thereon and described herein.

Figure 1 is an elevation, partly in section of an automatic scintillating sign.

20 Fig. 2 is an elevation of a specialized advertising cylinder.

Fig. 3 is a reduced size elevation of a rotating cylinder surrounded by a stationary casing in section.

25 Fig. 4 is a detached elevation of a part of the stationary casing shown in Fig. 3.

Fig. 5 is a reduced size plan view of Fig. 1.

30 Fig. 6 is a side elevation of the revolving sign shown in Fig. 3 combined with an individual letter cabinet.

Fig. 7 is a plan view of Fig. 6 showing a plurality of letter cabinets.

Fig. 8 is a front elevation of the sign portion of a letter cabinet having a curved face.

35 Fig. 9 is a front elevation of a letter cabinet having a straight sign portion.

Fig. 10 is an enlarged plan view partly in section of the tangential letter cabinet shown in the lower half of Fig. 7.

40 In practically carrying out my invention, I may use any desired type of incandescent lamp 1 mounted on a suitable receptacle 2 which is secured to a base 3. An outlet 4 serves for the cord which supplies the electricity for the lamp and a control switch, not shown, may be connected in this cord.

A wire or other support 5 is secured to the base 3 by means of a foot 6. This wire is bent at its upper end so as to terminate in a point 7 directly above the center of the lamp 1. This point 7 serves to support the propeller 9

which at its center is provided with a hollow glass or other suitable bearing 8. Outside of the blades of the propeller 9 an annular rim may be formed on which the cylinder 10 is supported by its inwardly projecting flange 11.

The lamp 1, base 3, support 5, propeller 9, and a cylinder 10 open at the bottom, constitutes all the required elements for producing an automatic self-acting advertising device. It is no departure from my invention to make the cylinder 10 an integral or rigidly attached part of the propeller instead of the drop on flange 11 shown in Fig. 1. The cylinder 10 may have an almost indefinite number of varying sized and shaped openings or windows formed in its wall; such for instance, as the individual letter windows 12, shown in Fig. 1, a single letter slit 20 and an entire word opening 21 shown in Fig. 3, or openings provided with guides 22 to receive a slip in translucent or transparent advertising tickets 23, or a large window 24 covered with a translucent material 28 shown in Fig. 2.

50 The window 24 covered by translucent material 28 may have any desired advertisement 25 printed thereon and parts of such advertisement may be in transparent form 27. To emphasize in brilliant contrast certain portions of the advertisement, slits or transparent portions 26 may be used. In addition, small perforations 14, similar to those shown in Fig. 1 as being formed in the translucent covering 13, may also be formed in the translucent covering 28.

55 The heat developed by the lamp 1 rises upward through the open bottom of the cylinder 10 and in passing by the blades of the fan 9 causes it to revolve at about thirty revolutions per minute, dependent more or less upon the weight of the cylinder. In so doing it successively brings into view from any portion of the entire three hundred and sixty degrees of its surrounding area whatever advertisement may be placed thereon, providing of course that such advertisement be either in transparent or semi-transparent form.

60 This type of device having a single rotating cylinder is equally effective and will carry its message to any one located at any point within its circumference. Whenever it is desired to direct the advertising message in a specific direction, then a stationary casing 15 may be used. This may have feet 18 between 65 which air inlet openings 19 are formed. The feet engage a circular ledge formed on the

upper face of the base 3 which serves to hold the casing concentric with the revolving cylinder 10. A single window 16 is formed in the casing 15 which is closed by a translucent covering 17. This may contain a single word, as shown in Fig. 4. As the cylinder 10 revolves in the direction to not spell the word shown in Fig. 4 backward, it is spelled letter by letter because the narrow window 20 will only admit light from the lamp 1 to illuminate a single letter at a given moment. This occurs once for each revolution of the cylinder 10 and also once for each revolution of this cylinder the window 21 comes into position so as to flash the entire word into view at one time, however, gradually bringing the light to the first letter first, and then to the second, etc., and lastly cutting off the light from the first letter first, gradually progressing to each of the other letters, in this way simulating the effect of the narrow window 20.

Whenever it is desired to more pronouncedly identify a single letter of a group of letters, the expedient shown on sheet 2 of the drawing, Figs. 6 to 10 inclusive, may be employed. This comprises a suitable base 29 which has a curved arc 32 formed at one end in order to fit against the base 3. From each end of the arc 32, radial edges 33 are formed ninety degrees from each other so as to permit a grouping of four individual bases, if desired, around a single rotating cylinder 10. On the base 29 standards or supports 30 are placed. These hold the letter compartment casing 31 which is provided with radial partitions 34 that are held in place by a bottom or floor 35 and a top cover 36. The inner or small end of the cabinet terminates in close proximity to the cylinder 10, and the outer face of the cabinet is closed by a translucent or transparent member 37 on which the individual letters are formed, as shown in Figs. 8 and 9. Two forms of casing 31 are shown in Fig. 7. The one to the right of the lamp terminates in the arc of a circle while the one shown below the lamp terminates in a straight line. Any number of partitions 34 may be used within the angular range of an observer's vision as may be desired, and in order to make the spelling visible within the entire circumference of the cylinder 10 the four casings may be duplicates of each other.

With my form of movable advertising signs and the use of translucent coverings combined with transparent openings or areas there is brought about a specially attractive result, because the maximum brilliancy of the lamps will intermittently show through such openings, thus producing a scintillating effect that compels attention and rivets the vision of an observer to the message of the advertisement. I do not of course limit myself to the use of the perforations in the translucent coverings where such coverings are placed

on the cylinder 10 or the casing 15 because, if desired, this expedient may also be used in the coverings 37.

With the individualized letter cabinet, shown on sheet 2, the successive spelling of a word is also due to the movement of the narrow slit 20 formed in the cylinder 10. One or more of these slits may be formed and they may be combined with a single wide opening 21 which will successively illuminate letter by letter, and at one time illuminate all the letters simultaneously similar to the effect produced by the openings 20 and 21 and the casing 15 shown in Figs. 3 and 4. It is apparent that by confining the luminosity between the partition walls 34, the transition from letter to letter will be more pronounced and in addition a greater length of space is thereby secured so that more letters can be used for a given advertisement.

It is of course obvious that I may almost unlimitedly change the expedients I have illustrated and described without departing from the spirit of my invention.

What I claim is:

1. In scintillating signs, a source of illumination, an enclosing cylinder supported for rotation above the source of light, means attached to the cylinder adapted to automatically rotate the same through air currents set in motion by the radiant heat of the source of light, and light transmitting advertising media secured to openings in the wall of the cylinder, said media comprising relatively large translucent areas and a plurality of small openings therethrough adapted to produce scintillations as the cylinder is rotated.

2. In animated signs, a rotatable cylinder, a source of light within the same, and light transmitting media having contrasting symbols formed thereon of relatively large translucent areas and having a plurality of small perforations therethrough said media being adapted to cover openings formed in the wall of the cylinder the perforations permitting rays to pass therethrough from the source of light in a scintillating manner as the cylinder rotates.

3. In scintillating signs, a rotatable cylinder, a suitable support therefor, a source of thermal luminosity within the cylinder, means attached to the cylinder adapted to be set into motion by the thermal radiations of the source of illumination, and means carried by the cylinder comprising translucent areas in the form of arbitrary symbols or letters of relatively large area for transmitting a portion of the luminosity and having a plurality of very small transparent areas conforming to the shape of the symbols adapted to make the luminosity within the cylinder visible in a scintillating manner.

4. A display sign comprising a plurality of contrasting symbols such as letters etc. formed on a translucent field surrounded by

an opaque area said symbols having a plurality of very small transparent areas grouped to conform to the shape of the symbols, means for maintaining a source of luminosity on one side of said areas, and means for producing movement between the luminous source and the symbols so as to project luminous rays through the very small transparent areas which through the movement between the source of luminosity and the letter areas produces a scintillating attention attracting effect.

5. An automatically movable sign for displaying characters or symbols comprising a source of illumination, a rotating opaque enclosure therefor, a plurality of translucently formed letter areas on the enclosure said translucent portions only transmitting a part of the luminosity and having a plurality of 10 smaller openings formed within the body of the letters or symbols, and means for rotating the enclosure by the radiant heat of the source

of illumination so as to produce attention attracting scintillations of light through the openings in contrast to the subdued luminosity coming through the translucent portions.

6. In automatic signs, a source of illumination, an opaque enclosure therefor formed in the shape of a tube or cylinder provided with a plurality of semi-transparent letters or symbols within its wall each semi-transparent area having a plurality of small transparent areas or openings grouped to conform to the shape of the letters or symbols, and means for 15 rotating the enclosure around the source of illumination to thereby continuously and successively bring into scintillating visibility the transparent areas in contrast with the semi-transparent shapes of the letters or symbols 20 throughout an entire rotation of the enclosure.

In testimony whereof I affix my signature.
ARTHUR W. SIEVERS.
